PROCESS FOR FORMING PANELS IN SHEETS

Filed May 8, 1930

UNITED STATES PATENT OFFICE

ARVID ANDERSON, OF CHICAGO, ILLINOIS, ASSIGNOR TO MORTON MANUFACTURING COMPANY, A CORPORATION OF ILLINOIS

PROCESS FOR FORMING PANELS IN SHEETS

Application filed May 8, 1930. Serial No. 450,644.

My invention covers an improved process for making recessed or raised panels in metal sheets for use in the construction of metal doors, partitions, or the like.

5 In the construction of doors, partitions or the like it is very desirable to have paneling to simulate the paneling in wooden doors or partitions. The procedure heretofore resorted to for forming such paneling is cumbersome and expensive as each panel is formed with a single operation of a die structure. The procedure thus requires a 10 separate set of dies for each panel size and where the paneling is large the dies are heavy, cumbersome and expensive. Furthermore, the procedure requires comparatively 15 large presses.

An important object of the invention is to provide a simple process requiring only a 20 few and extremely simple die elements by means of which a metal section for defining a panel may be progressively deflected in the metal sheet in which the panel is to be formed.

25 A further object of the invention is to provide procedure for assuring sharp and well defined corners for the panels formed by the dies, this being accomplished by punching holes in the metal sheet for defining the corners of the panel to be formed and for affording clearance and relief spaces for the metal at the corners so that this metal will not crimp or fold but will form a smooth well-defined and sharp corner.

30 Another feature of the invention involves the refilling of the corner openings with pieces of metal welded or otherwise secured, to entirely and smoothly refill the holes.

Referring to the drawings, Figure 1 is a 35 front elevation of a panelled metal sheet,

Figure 2 is an enlarged section on plane II-II of Figure 1, showing the die members in front elevation after having formed the corresponding side of the panel,

40 Figure 3 is an enlarged section on plane III-III of Figure 1 showing the relief openings,

Figure 4 is a section similar to Figure 3 showing the openings refilled, and

45 Figure 5 is an end view of the die mem-

bers of Figure 2 and the formed plate therebetween.

Figure 1 shows a metal sheet 10 having therein a large lower panel 11 and a number of smaller upper panels 12. This sheet 55 may form one side of a door or partition, a sheet such as shown and a companion sheet being properly spaced and secured at their edges to form the door, partition, or other unit or structure.

60 Referring to Figures 2 and 3, the lower die member 13 may be a bar of sufficient length for the longest side of the largest panel. The bar has the upper side or surface 14 for receiving the metal plate, and a 65 lower parallel surface 15 for receiving the depressed section 16 which forms the panel. The surface 17 intermediate the steps 14 and 15 is inclined, usually at 45°, to receive the section 18 for forming a side of the panel.

70 For the upper die members 19 die bars are used of lengths corresponding to the lengths of the panel sides to be formed. For example, to form the large panel 11, there would be an upper die bar of a length corresponding to that of the short vertical sides 75 of the panel, and another bar having a length corresponding to the lengths of the upper and lower horizontal sides of the panel. The upper die bars are shaped to fit the lower die bar 18 and each has a horizontal under-surface 20 for engaging the top of the metal plate 10, an under-surface 21 below the surface 20 for engaging the section 16 to be deflected, and an intermediate under surface 80 22 at an angle of 45° for forming the side section 18 of the panel. The die members 19 are of a length to overlap the deflected panel a distance as shown in Figure 2, and 85 inwardly of the ends; they are cut away at 45° to provide the surfaces 23 for engaging with or defining the ends of the panel sides which extend at right angles from the side being formed. For example, Figure

90 2 shows a panel side α being formed, the intermediate diagonal section 18 being formed between the diagonal surfaces 17 and 22 of the die members 13 and 19 respectively, while the diagonal corners 23 of the upper die member will engage with and hold the 95 100 panel side α .

ends of the diagonal section *b* at the horizontal sides of the panel if such sections have already been formed, or to define the beginning of such sections if they have not already been formed.

5 After the vertical sides of the panel have been formed, first one and then the other, then a longer upper die bar is taken and the horizontal sides of the panel are formed, first one and then the other.

10 In order to relieve the metal of strain at the corners of the panel during forming thereof and to provide clearance in order to prevent buckling, folding, or other distortion of the metal adjacent to the panel corners holes 24 are punched in the metal sheet before the panel is formed, these holes being spaced to define the corners of the panels and may be of various shapes, as for example 15 triangular, rectangular, circular, or otherwise. When the panel is formed its corners merge into these holes, and the holes are then refilled by inserting therein pieces 25 of metal which are welded or brazed into position, and then by grinding or filing 20 the outer faces of the pieces are smoothed down to be flush with the surface of the plate.

To form the upper die members 19, long stock bars of suitable metal may be planed or 30 cut to form the die surfaces 20, 21 and 22, and then the bars may be cut into lengths suitable for the panels to be formed, the corners of the lengths being then cut away to leave the diagonal end die surfaces 23.

35 The lower or female die member 13, instead of being a continuous long bar, may be built up on the press of shorter sections to the length required for the desired die operation.

40 By means of my process, the use of heavy cumbersome dies is avoided as the same work can be efficiently accomplished by the lighter and less expensive die elements, and lighter presses can be used.

45 Having described my invention, I desire it understood that although I have illustrated and described in detail the preferred embodiments of my invention, the invention is not to be thus limited but only in so far 50 as defined by the scope and spirit of the appended claims.

I claim as follows:

1. The process of forming a panel in a metal sheet which consists in first punching 55 holes in the sheet to define the corners of the panel, and then by separate die operations successively depressing the metal between the holes to form the sides which define the panel.

60 2. The method of forming a panel in a metal sheet which consists in first punching clearance and release holes through the sheet to define the corners of the panel, then by 65 separate steps deflecting the metal between

such holes to form one at a time the sides for defining the panel.

3. The process of forming a panel in a metal sheet which consists in first punching holes through the sheet to define the corners 70 of the panel and to form a clearance and relief spaces for deflected metal, then by separate die operations deflecting narrow sections of the metal between said holes to form the sides surrounding the deflected panel sec- 75 tion, and then refilling said holes.

4. The process of forming a panel in a metal sheet which consists in punching holes through the sheet to define the location of the panel and to afford clearance and relief 80 spaces, then depressing the section of the sheet between said holes to form the panel, and then refilling the holes.

In testimony whereof I have hereunto subscribed my name at Chicago, Cook County, 85 Illinois.

ARVID ANDERSON.
